SWING

Roy Glenn Low, Minneapolis, Minn.

Application April 17, 1950, Serial No. 156,294

5 Claims. (Cl. 155—65)

1.

My invention relates to swing structures and, more specifically, to infants' swings of the indoor type adapted to be suspended from the ceiling or other overhead structure.

The primary object of my invention is the provision of a swing structure which is capable of providing a maximum of entertainment for the occupant.

A still further object of my invention is the provision of a swing generally resembling an airplane, including wings and propellers and retractable landing wheels.

A still further object of my invention is the provision of an infants' swing structure of the class described, which is relatively inexpensive to produce, rugged in construction, simple in operation, and durable in use.

The above and still further objects and advantage of my invention will become apparent from the following detailed specification, appended claims, and attached specification.

Referring to the drawings, wherein like characters indicate like parts throughout the several views:

Fig. 1 is a perspective view of my novel invention;

Fig. 2 is a view in side elevation;

Fig. 3 is a view in front elevation;

Fig. 4 is an enlarged fragmentary view in front elevation of a portion of the frame of my novel device, some parts being broken away and some parts shown in section;

Fig. 5 is an enlarged sectional view taken on the line 5—5 of Fig. 4; and

Fig. 6 is an enlarged sectional detail taken on the line 6—6 of Fig. 1.

Referring with greater particularity to the drawings, the numeral 1 indicates, in its entirety, a seat portion having a reduced forwardly-projecting straddle tongue 2, side-forming members 3, and a back member 4. Secured to opposite sides of the members 3, by means of headed bolts or the like 5, are ball-shaped trunnions 6, which are snugly received within socket elements 7 rigidly secured to the lower ends of ropes or the like 8 adapted to be secured to the ceiling or other overhead structure not shown. At its front end, the straddle tongue 2 is provided with a tubular bearing 9 formed by bending a metal plate 10 backwardly upon itself. As shown in detail in Fig. 5, screws 11 retain the plate 10 in place.

A generally upright frame made up of side frame members 12 and an intermediate frame member 13, shown as being tubular in form, is pivotally connected intermediate its upper and

lower portions to the front end of the straddle tongue 2 by means of a transverse pivot rod 14 extending through the bearing 9. As shown in Fig. 5, the rod 14 is secured by welding or the like at its opposite ends to the intermediate portions of the side frame members 12. Preferably and as shown, the side frame members 12 are joined at their lower ends to provide a foot rest 15 and project rearwardly and outwardly at their upper ends to provide spaced gripping handles 16. Furthermore, when it is desirable, the elements 12, 15, and 16 may be formed from a single length of stock.

At its lower end, the tubular intermediate frame member is secured by welding or the like to the forward side of the foot rest 15 intermediate its ends, as indicated at 17 and as shown particularly in Figs. 4 and 5. At its upper end, the tubular frame member 13 is secured by welding or the like to the upper ends of the side frame members 12 by means of connecting bars 18 (see particularly Fig. 3). At its intermediate portion, the tubular frame member is provided with an elongated transversely-extended slot 19 which extends therethrough. A pair of arms 20 are pivotally secured intermediate their ends, as indicated at 21, one each to the intermediate portions of side frame members 12. The inner ends of the arms 20 are reduced, as indicated at 22, and are provided with opposed flat contacting surfaces 23. By reference particularly to Figs. 1 and 4, it will be seen that the reduced ends 22 of the arms 20 are snugly slidably received in face-to-face relationship within the slot 19 for limited vertical movements. The outer ends of the arms 20 are provided with wheels 24 preferably rubber tire-equipped.

The tubular intermediate frame member 13 is closed at its bottom, as indicated at 25. In the lower portion of the tubular member 13, interposed between the closed bottom 25 and the crossed reduced ends 22, is a coil compression spring 26 which yieldingly biases the reduced end portions 22 to the upper limits of the slot 19, as shown particularly in Fig. 4, whereby to position the wheels 24 at a level below the frame members 12 and 13 and the foot rest 15. In its upper end, the tubular intermediate frame member 13 is provided with a plunger 27. The upper end portion 27a of the plunger 27 is bent at substantially right angles to the axis of the member 23, and projects outwardly through and is slidably received within a longitudinally-extended bayonet slot 28 having the angularly-disposed portion 29 at its lower end. As shown

particularly in Fig. 2, a mounting bracket or plate 30 is secured to the upper ends of the frame members 12 and 13. A transversely-extended wing member 31 is secured by means of screws or the like 32 to the frame member 30 (see Fig. 3). A pair of simulated motor mountings 33 project forwardly from the leading edge of the wing member 31 in laterally-spaced relationship. Mounted for rotation to each of the members 33 is a propeller 34 which will be rotated by the air upon movement through the air in opposite directions, as the swing is put into operation. To suspend the forward end of the swing, I provide a pair of rope members 35 which preferably extend through spaced openings 36 in the wing member 31. The 15 looped lower ends 37 of said ropes are loosely received within eyes 38 welded or otherwise rigidly secured to the lower portions of the side frame members 12.

For proper operation of my novel structure, the rope members 8 and 35 are secured to a ceiling or otherwise a overhead supporting structure not shown, so that the seat 1 is in a substantially horizontal position with the wheels 24 just engaging the floor or other surface over which the swing is to be operated. Then, as swinging movements are imparted to the swing, the wheels 24 make contact with the floor sufficiently to cause pivotal movements of the connected frame members 12 and 13 about the pivot rod 14. These movements are indicated by dotted lines in Fig. 2. Furthermore, the wheels 24 are caused to be pushed upwardly slightly to absorb any shock which would otherwise be imparted thereto. The pivot movements of the frame about the pivot rod 14, together with the lifting movements of the wheels 24, allows a great deal of action and amusement for the occupant, with complete freedom from breakage. Furthermore, when it is desired to retract the 40 wheels 24 upwardly from the full line position of Fig. 3 to the dotted line position thereof, the angularly-disposed end 21a of the plunger 21 is moved downwardly and angularly sideways to engage the portion 29 of the bayonet slot 28.

My device has been thoroughly tested and found to be thoroughly satisfactory for the accomplishment of the above objects; and, while I have shown a preferred embodiment of my invention, it should be obvious that the same is capable of modification without departure from the scope of the appended claims.

What I claim is:

1. In a swing of the class described, an upright frame, a seat having an elongated forwardly-projecting straddle tongue, means mounting the front end of said tongue to said frame member for pivotal movements of said frame with respect to said seat about a horizontal axis, a wing structure secured to the upper end portion of said frame, handle members on said frame rearwardly of said wing structure, a pair of spaced supporting ropes secured at their lower ends to the lower end portion of said frame and extending upwardly through spaced openings in said wing structure, a pair of supporting ropes secured at their lower end portions to said seat, said ropes being adapted to suspend said frame and seat in spaced relation to the ground when connected to suitable supporting means, a pair of laterally-spaced retractable landing wheels, and means mounting said wheels on said frame for movements from operative floor-engaging positions below the plane of said frame to inoperative retractive positions above the plane of the bottom of said frame.

2. In a device of the class described, an upright frame, a seat having an elongated forwardly-projecting straddle tongue, means mounting the front end of said tongue to the intermediate portion of said frame for pivotal movements of said frame with respect to the seat about a horizontal axis, a wing structure secured to the upper end portion of said frame, handle members on said frame rearwardly of said wing structure, means for securing said frame and seat from an overhead support for swinging movements, said frame including a pair of connected spaced side frame members and an intermediate vertical frame member, a pair of arms pivotally secured intermediate their ends one each to one of said side frame members, means slidably connecting the inner ends of said arms to said intermediate frame members, wheels adjacent the outer ends of said arms, and means yieldingly biasing said arms toward a position where said wheels project below the level of said frame.

3. The structure defined in claim 2 in which said side frame members are connected at their lower ends to provide a foot rest and in which the upper ends of said side frame members extend rearwardly to provide said handle members.

4. The structure defined in claim 2 in which the intermediate frame member is tubular and is provided with an elongated slot intermediate its ends, and in which the inner ends of the arms are reduced, the reduced ends of said arms being snugly received within said slot for limited vertical sliding movements, said yielding means comprising a coil spring in said intermediate frame member.

5. In a device of the class described, an upright frame, a seat having a forwardly-projecting straddle tongue, means mounting the front end of said tongue to the intermediate portion of said frame for pivotal movements of said frame with respect to said seat about a horizontal axis, a wing structure on the upper end portion of said frame, said frame comprising spaced side frame members and a tubular vertical intermediate frame member, said side frame members being joined together at their base to provide a foot rest and extending rearwardly at their upper ends to provide spaced handle members which project rearwardly of said wing structure, the central portion of said intermediate frame member being transversely slotted, a pair of arms pivotally secured intermediate their ends to one each of said side frame members, the inner ends of said arms being snugly slidably received in side-by-side relation within said slot, the outer ends of said arms being provided with wheels, a coil spring within the lower portion of said intermediate frame member yieldingly biasing said arms in a direction to project the wheels below the level of said frame, a plunger in the upper portion of said tubular intermediate frame member engageable with the inner ends of said arms, and means for locking said plunger in a position to maintain the wheels on the outer ends of the arms in a position above the level of the lower end of said frame.

ROY GLENN LOW.
